UNITED STATES PATENT OFFICE.

STANLEY M. WATANABE, OF MOUNTAIN VIEW, CALIFORNIA.

DESIGN FOR A CANDY TABLET.

50,538.

Specification for Design.

Patented Mar. 27, 1917.

Application filed October 3, 1916. Serial No. 123,596. Term of patent 14 years.

To all whom it may concern:

Be it known that I, STANLEY M. WATANABE, a subject of the Emperor of Japan, residing at Mountain View, in the county of Santa Clara and State of California, have invented a new, original, and ornamental Design for Candy Tablets, of which the following is a specification, reference being had to the accompanying drawings, forming part thereof.

Fig. 2, is a side view of a candy tablet showing my new design.

I claim:

The ornamental design for a candy tablet, as shown.

STANLEY M. WATANABE.
